METHOD OF AND APPARATUS FOR AMPLIFYING AND PROJECTING SOUND WAVES

Application filed January 9, 1929. Serial No. 331,343.

My present invention is primarily concerned with amplifying and projecting sound waves from reproducers such as are commonly used for phonographs and radio, but it 5 will be obvious that the principles of my invention are applicable to sound waves from other sources.

My invention is based upon the discovery that sound waves may be improved in quality 10 by projecting them through a tortuous amplifier in which the waves are reflected many times, preferably at substantially right angles, and that this may be accomplished without appreciably damping or distorting 15 waves of the more uniform or musical frequencies, yet with a material dampening, wearing out and muffling of waves of irregular or noise frequencies. The result is a sweetening and purification of the sound.

20 For such purpose, I prefer that the amplifying conduit have non-resonant walls, because resonant amplifiers have a tendency to impose their own frequencies upon the sound waves which pass therethrough, thereby 25 disproportionately and unduly magnifying certain tones.

As the result of my discoveries, I have devised an amplifying means and method which assures the sweet, true amplification of musical sounds, the sound waves of regular frequencies being truthfully amplified without distortion, while the sound waves of irregular frequencies, such, for instance, as needle noises and other noises introduced by 30 mechanical defects in the recording or reproducing apparatus are subdued in the amplifying projector.

In accordance with the preferred embodiment of the invention I provide an amplifier 40 consisting essentially of two spaced parallel non-resonant walls, affording a tortuous pathway for the sound waves formed by articulating reflector surfaces on the opposed faces of the discs. Such surfaces may be conveniently formed by deep concentric corrugations or grooves in the opposed disc faces.

Where longer air columns are required for relatively deep-toned amplifiers, the disc corrugations may be supplemented by articulating 45 concentric partitions on the discs. These

partitions produce a radially labyrinthine air column of any desired length including a plurality of connected annular legs. The deflector surfaces direct the waves from one leg of the column into the next without distortion. Wave front expansion occurs only as the wave front is deflected from the end of one column leg into the next one. During the passage of the waves through the column legs, at right angles to the radius, no expansion occurs, so that I have in effect any desired length of labyrinthine air column through which sound waves of regular frequency are propagated without distortion or muffling while being continuously confined against lateral expansion in one direction and intermittently expanded at predetermined intervals in the other direction, the amplification being accompanied by the subduing of undesirable noises.

The column legs serve in each instance to more or less realign and reunite the wave front and direct it at a true 45° angle against the next deflecting surface. The annular nature of the chamber sections where expansion occurs permits such expansion at the maximum rate of speed during the expansion cycles or in other words at a rate which equals the propagation rate multiplied by 2π .

The path followed by the reflected waves, that is, the effective air column length, is twice the straight line distance from the entrance to the exit of the projector, plus the lengths of the partitions, when the latter are used. Where no partitions are used, at least one-half of the length of wave front travel will be in a non-radial (non-expanding) direction and the expansion is in effect intermittent, although there is no opportunity to mechanically realign or redirect the wave front between successive deflecting surfaces.

The discs may be made of heavy material, such, for instance as cast metal, so that their natural frequencies are beyond the normal range of musical notes and sympathetic vibration producing audible resonance will not be set up in them by the vibrating air column which they confine. They may be stamped from heavy sheet metal and their

corrugated backs filled with plaster of Paris or the like.

The tortuous conduit, passageway or amplifying chamber which is provided by the opposed faces of the discs or by such faces in combination with the labyrinthine partitions, not only provides a series of wave reflecting surfaces which wear out and damp out the undesirable waves or irregular frequencies but materially assists in loading the diaphragm or other propagating element, since the load of any air column in a tortuous chamber exceeds load of a column of similar length in a straight chamber. These corrugations and partitions furthermore control the ratios of total wave front expansion to total distance of wave propagation, and this seems to be an important factor in effectively loading or coupling the air column to the diaphragm for efficient air wave generation and propagation, particularly with respect to the longer wave lengths.

The invention may be more fully understood from the following description in connection with the accompanying drawings, wherein:

Fig. 1 is a transverse sectional view through a non-resonant amplifier embodying the invention;

Fig. 2 is a reduced front elevational view thereof with parts of the front disc broken away;

Fig. 3 is a fragmentary view similar to Fig. 1, but illustrating a slight modification;

Fig. 4 is a view similar to Fig. 1 and illustrating a further modification;

Fig. 5 is a partial front elevational view of the amplifier shown in Fig. 4, and with parts broken away and in section for clearness.

In Figs. 1 and 2, I have shown a comparatively simple elementary embodiment of the invention, in which a pair of spaced, parallel non-resonant discs 10 and 11, cooperatively define the amplifying chamber. These discs are preferably of fairly heavy cast metal construction. Disc 11 has an opening 12 at its center constituting a throat through which sound waves from any ordinary electromagnetically actuated diaphragm reproducer unit such as 13 are directed into the center of the amplifying chamber. Radially beyond the disc 10, the disc 11 is provided with a bell or flare 22 serving as a mouth piece to properly direct the amplified sound waves which issue radially from between the disc edges. Spider legs 30 projecting inwardly from horn 22 support disc 10 in proper position.

The opposed faces of the two discs are annularly ribbed or corrugated with a series of equi-distantly spaced, regular corrugations 10a and 11a, these corrugations considered cross-sectionally having right angular apices and defining grooves between them of similar cross-sectional shape. The corrugations of one disc alternate and articulate

with those of the other, all corrugation apices being preferably in the same plane so that the exposed disc faces cooperatively define a regularly-tortuous, circular amplifying chamber through which sound waves entering centrally from the throat 12 are radially propagated, their wave fronts expanding circumferentially only. Each successive rib face is in position to intercept and deflect through 90°, to the next face, the direct reflections from the preceding face.

In the course of their travel from the center of the chamber to the outer periphery thereof, the waves will be reflected back and forth striking against all of the deflecting surfaces which are formed by corrugations 10a and 11a, the axis of travel of the waves being indicated in dotted lines in Fig. 1. Such minor parts of the waves as are not intercepted at the 45-degree angle will be subject to progressively confusing reflections and will be dissipated. The path of travel of the orderly reflection, in passing from the center to the outer edge of the chamber, is twice as long as the distance which would be traveled if the faces of the discs were uncorrugated and the waves could travel in a straight line, half of the wave travel being non-radial and non-expanding.

The most rapid wave front expansion obtainable between parallel surfaces is circular expansion, which is approximately 6 to 1. For instance, if circular, the expansion chamber of Fig. 1 is 12 inches in diameter, then without the deflecting surfaces, a sound wave in traveling 6 inches from the disc center to the disc edge would have expanded to approximately 36 inches, but with the deflecting surfaces, the reflected wave must travel 12 inches to expand to 36 inches, an over-all ratio of approximately 3 to 1. The expanding part of this travel, however, is only 6 inches and is at the same rate as if there were no reflections, namely, 6 to 1. The difference is that the air column length is twice as great and the multiple reflections have the desired smoothing effect on the waves. Thus the 3 to 1 ratio is merely a distance ratio, not a speed ratio and the distance ratio controls primarily the diaphragm air-column load. This may be considerably increased without in any way varying the preferred maximum expansion ratio of 6 to 1, or any other ratio which may be arbitrarily selected, as by making the passage semi-circular or following the surface of a cone.

In Fig. 3, I have illustrated a slight modification in which discs 10b and 11b corresponding to the discs 10 and 11 are similarly arranged to form an amplifying chamber. In this case, instead of using right angular corrugations, I utilize semi-circular grooves 14 properly articulated to give the equivalent of 2 right angular deflections, the total of which is 180 degrees, while preserv-

ing a chamber of uniform width throughout. Throat 12a and horn 22a corresponding to throat and horn 12, 22 of Fig. 1 are retained. Here the axis of wave travel is substantially the same as the wave travel illustrated in Fig. 1, but the surfaces not being plane, the flanks of the wave front, make the 180 degree turns by many small angle reflections. The rounded grooves give a somewhat more mellow rolling tone to music than the angular grooves, but the latter give better articulation.

In Figs. 4 and 5, I have shown a modification which permits the use of a considerably longer air column without radially increasing the size of the amplifier. The distance ratio of expansion to propagation has been changed from approximately 3 to 1 to approximately $\frac{1}{2}$ to 1, yet at the places where expansion occurs, the ratio of expansion to propagation remains the same, about 6 to 1. In this form of the invention, a pair of relatively widely spaced non-resonant discs 10c and 11c are provided, these discs being conveniently stamped from some heavy material and having the corrugations in their outer sides filled with plaster of Paris or equivalent material 16 which militates against resonance. The corrugations in the discs are similar to those shown in Fig. 1 and at the peak of each corrugation there is provided a non-resonant circular wave-guiding partition 17 adapted to enter between and properly articulate with the similar partitions of the opposite disc. Throat 12b and bell 22b corresponding to the throat and bell 12, 22 of Fig. 1, are retained and legs 30a support disc 10c from the horn 22b.

Inasmuch as squeezing of the air column at any point is to be avoided, I prefer to make the entering throat 12b of the amplifier of a cross-sectional area which is at least as small as the cross-sectional area of the first annular leg or portion of the amplifying chamber into which the wave front is directed. A similar condition is true in Figs. 1 and 3, in that the total cross-sectional area of the throat 12 or 12a is no greater than the annular cross-sectional area of the amplifying chamber at the point where the amplifier chamber and throat communicate.

With this form of the invention, I have provided a radially labyrinthine amplifying passage, the labyrinth being formed by a series of concentric serially connected annular portions, the combined length of which is determinative of the total air column length of the amplifier. The sound waves in passing from the center of the chamber to a point of discharge at the outer end of the chamber are, during the major portion of their travel sustained against expansion in any direction. As they are deflected from one leg of the labyrinthine chamber into the next leg thereof expansion occurs and it will

be seen that the non-radial or non-expanding travel cycles of the wave front greatly exceed the radially propagating and expanding cycles.

The principal difference between Fig. 1 and Fig. 4 is the fact that the latter figure shows a construction with a longer air column and consequently an amplifier better adapted to project longer sound waves, characteristic of lower frequencies. Moreover, the diffused and irregularly reflected parts of the waves are more completely subdued. The sound cannot "short-circuit" radially from the entrance to the exit. The clarity and truthfulness of the amplified sound and the subduing of undesirable noises is common to both constructions as is the actual rate of wave expansion.

Air column length may be increased or decreased without corresponding increase or decrease in the number of reflecting surfaces employed or the size of the amplifier, by simply varying the length of some or all of the partition walls 17.

Air column length is an important factor primarily because it controls the dominating tonal quality and the sonority of the amplifier and is an important factor in controlling the loading of the diaphragm. That is to say, an ordinary reproducer diaphragm without any projector is extremely ineffective, apparently because the waves are radiated directly and the wave front expands as the square of the distance of propagation. The sound produced is surprisingly weak because the air is not properly confined, or, so to speak, "loaded" onto the diaphragm. The circular expansion between confining surfaces, giving a 6 to 1 expansion is insufficient for the purpose. By the present invention, I accomplish the desired circular expansion at intervals and utilize the non-expansion intervals to increase air column length and the diaphragm load. It will thus be seen that the diaphragm loading while depending, of course, to a certain extent on the total length of the air column is even more directly dependent upon the distance ratio of wave propagation to wave front expansion and that the present invention enables me to combine the desirable maximum expansion rate of the wave front without any corresponding loss in the effective diaphragm loading.

The damping out of the irregular or noise frequencies seems to depend much less on air column length than on the number of reflecting surfaces against which the waves are caused to impinge. This factor of the number of reflector surfaces used is also capable of arbitrary predetermination without regard to air column length either by using smaller ribs on more closely spaced confining discs, or larger ribs with greater spacing, or by using a greater or less number

of partitions to make air column legs of any desired length.

So long as the wave reflections are at right angles or substantially at right angles, tonal quality of the amplifier seems to be variable independently of the number of reflecting surfaces used and to be directly proportional to the effective air column length. In other words, even a very great number of right 10 angular reflections seem inoperative to deaden or distort waves of regular frequencies.

From the foregoing, it will be seen that a desirable embodiment of the invention involves the use of an amplifying conduit 15 which confines the wave fronts against expansion in one dimension and permits their circular expansion in the other dimension, at intervals and for distances required to afford a total air column of sufficient length to give 20 the desired tonal qualities together with means for right angularly deflecting the waves in their course of travel through the conduit whereby undesirable noises are subdued without detriment to sound waves of 25 regular frequencies.

As pointed out above, by the proper design of the apparatus, the air column length and the number of deflecting surfaces can be varied independently of each other. The 30 rate of the wave front expansion, where there is any, is a constant factor, but the frequency and length of the expansions is subject to variation entirely independently of air column length. In this connection, for 35 instance, I might simply radially extend the two discs of Fig. 1 until they confined an air column equal to the total air column length of Fig. 4. I would thus have a number of expansion zones far greater than those permitted by the device of Fig. 4 and yet have 40 the same air column length and consequently the same tonal quality and sonority.

While I have discussed throughout the use of an amplifying chamber of general 45 circular form which permits radial wave propagation accompanied by circular wave front expansion intervals, it is within the spirit of the invention to utilize amplifying chambers of less than circular shape, for instance, of semi-circular or sectoral shape. When such chambers are used, it is never 50 possible to obtain maximum rate of wave front expansion and a sectoral chamber must be of considerably longer radius 55 than a circular chamber in order to accomplish expansion of the wave front to a similar extent. On the other hand, with a sectoral chamber only the curved side of the chamber will be open and I will have 60 in effect a four-walled amplifier which of course facilitates diaphragm loading. When the column is confined on four sides instead of two, the ratio between wave propagation and wave front expansion becomes a much 65 less important factor in the final determina-

tion of diaphragm loading. In other words, the more the amplifying chamber is restricted, the more air column length becomes the dominating factor in diaphragm loading and the less significant becomes the distance ratio of wave propagation to wave front expansion. An extreme example of this is where the wave is propagated through a chamber which permits no expansion. In this instance, the only factor other than air 70 column length which would be determinative of diaphragm loading would be the added frictional resistance to wave motion which is an incident of the undulations or corrugations in the chamber walls. 75

I claim:

1. A method of amplifying sound which consists in propagating sound waves from a center through a tortuous conduit, repeatedly right angularly reflecting the wave while circularly expanding it in one dimension, at intervals and preventing expansion thereof in the other dimension. 80

2. A method of sound amplification which includes propagating sound waves radially through a conduit having a circumferential open mouth, repeatedly reflecting the waves at right angles during the course of their passage through the conduit and intermittently circularly expanding the waves in one dimension only. 90

3. A method of amplifying sound which includes passing the sound waves through an open mouthed conduit which is continuously expanding in one dimension only and repeatedly deflecting the waves at right angles during the course of their passage through the conduit. 100

4. A method of amplifying sound which consists in propagating sound waves through a conduit, preventing expansion of the wave front in one dimension, intermittently radially expanding it in the other dimension, and deflecting the wave front at right angles at least once between each expansion cycle. 105

5. A method of amplifying sound which consists in propagating sound waves through a conduit, repeatedly reflecting the wave front at substantially right angles and alternately permitting and preventing wave front expansion in one dimension only between consecutive deflections. 110

6. A sound amplifier including a pair of spaced parallel discs, each of heavy non-resilient cast metal, one disc having a central opening therein through which sound waves enter the space between the discs, and means on the opposed disc faces coacting to define a radially tortuous passageway through which the waves are radially propagated and circularly expanded. 115

7. A sound amplifier including a pair of spaced parallel discs, each of heavy non-resilient cast metal, one disc having a central opening therein through which sound waves 120

enter the space between the discs, and means on the opposed disc faces coacting to define a radially tortuous passageway through which the waves are propagated, said means comprising alternating annular concentric ribs and grooves on one disc registering with similar ribs and grooves on the other disc.

8. A sound amplifier including a pair of spaced parallel discs, each of heavy non-
10 silient cast metal, one disc having a central opening therein through which sound waves enter the space between the discs, and means on the opposed disc faces coacting to define a radially tortuous passageway through

15 which the waves are propagated, said means baffling straight radial propagation of the wave front and causing it to travel in a regularly repeated series of right angular deflections.

20 9. A sound amplifier including a pair of spaced parallel discs, one disc having a central opening therein through which sound waves enter the space between the discs, and means on the opposed disc faces coacting to define a radially tortuous passageway through which the waves are propagated, said means baffling straight radial propagation of the wave front and causing it to travel in a regularly repeated series of right angular deflections, which are alternately in radial and non-radial directions, whereby the wave front is intermittently circularly expanded in one direction.

10. A sound amplifier including opposite
25 walls the opposed faces of which form parallel surfaces of revolution and define a radially expanding passage, a central opening in one of said walls through which sound waves are introduced, said walls preventing wave expansion in one direction and their opposed faces providing alternating concentric circular ribs and grooves, the ribs and grooves of one wall registering respectively with the grooves and ribs of the other, and all of the
30 rib apices lying in common surface of revolution parallel to the planes of the walls.

11. A sound amplifier including opposite walls the opposed faces of which form parallel surfaces of revolution and define a radially expanding passage, a central opening in one of said walls through which sound waves are introduced, said walls preventing wave expansion in one direction and their opposed faces providing alternating concentric circular ribs and grooves, the ribs and grooves of one wall registering respectively with the grooves and ribs of the other, and all of the
35 rib apices lying in common surface of revolution parallel to the planes of the walls, and each groove providing a pair of deflecting faces effective to reflect a wave through a total angle of 180 degrees.

12. A sound amplifier including a pair of spaced parallel discs forming a radially ex-
40 panding passage, one of said discs having a

central opening therein through which sound waves are introduced, the faces of each disc being regularly circularly concentrically corrugated to define alternating ribs and grooves registering respectively with the grooves and ribs of the opposite disc, the apices of the ribs and grooves being cross-sectionally rectangular and the discs being spaced apart sufficiently to dispose all rib apices in a common plane.

Signed at New York, in the county of New York, and State of New York, this 18th day of October, A. D. 1928.
